UNITED STATES PATENT OFFICE.

JOSEPH A. GRABENSTEIN, OF CUMBERLAND, MARYLAND.

ELECTRIC TOY.

Application filed April 7, 1924. Serial No. 704,841.

To all whom it may concern:

Be it known that I, JOSEPH A. GRABENSTEIN, a citizen of the United States, residing at Cumberland, in the county of Allegany and State of Maryland, have invented new and useful Improvements in Electric Toys, of which the following is a specification.

This invention relates to improvements in electrically driven toys which run on tracks, the general object of the invention being to provide means for causing the toy to come to a standstill for a certain period of time and then to start moving along the track again, thus adding to the novelty of the device by automatically bringing it to a stop occasionally during its actuation.

Another object of the invention is to provide means for adjusting the stop periods of the device.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is an elevation of a casing containing the attachment.

Figure 2 is a section on line 2—2 of Figure 1.

Figure 3 is a section on line 3—3 of Figure 2.

Figures 4 and 5 are face views of the switch disc.

Figure 6 is a diagrammatic view showing the invention attached to a circular track.

In these views, 1 indicates the rails of a circular track and 2 the third rail, one of the rails 1 and the rail 2 being connected with a suitable source of power by the conductors 3 which are connected with the usual transformer 4. A motor 5 is connected with the conductors and rheostats 6 are arranged in the circuit for controlling the flow of current to the motor and to the third rail. As will be understood, when a toy, such as a train of cars, is placed on the track a part thereon will bridge the third rail and the track so that the circuit will be completed to the motor on the toy so that the same will be

caused to move along the track. In carrying out my invention I insulate a portion 7 of the third rail from the rest of the rail so that when the toy reaches this dead section 60 the supply of current to its motor will be cut off and the toy will come to rest. In order to cause the toy to begin to move again I provide means for supplying current to the section 7 after a certain period of time, 65 such means consisting of a disc 8 of insulating material mounted on a shaft 9 which is connected by a chain of gearing to a shaft 10 which is driven from the motor 5 by means of the belt 11 and the pulleys 12, the chain 70 of gearing being enclosed in a casing 13. The disc 8 carries a curved contact strip 14 which is adapted to contact with a contact point 15, preferably formed of carbon, and which is held in engagement with the disc 75 by a spring contact 16 which is electrically connected with the live part of the third rail by a conductor 17. This spring contact is adjustable by means of the screw 18 and the member 15 is slidably mounted in a partition 80 19 of the casing 20 which encloses the motor, the disc and their associated parts. This casing and partition are formed of insulating material. The metal shaft of the disc 8 is connected with the strip 14 by a conducting 85 strip 21 and the current will flow from said metal shaft through the metal parts of the gear train to the conductors 22 which are connected with the portion 7 of the third rail.

It will thus be seen that the disc 8 is rotated from the motor 5 and until the strip 14 in the disc 8 is brought into engagement with the contact 15 no current will be supplied to the portion 7 of the third rail so that 90 when the toy reaches this portion of the third rail it will come to rest as its motor will not receive any current. The toy will remain idle until the disc is turned to bring the contact strip 14 against the contact member 15, when current will be provided to the section 7 through the live part of the third rail, the conductor 17, strip 16, member 15 and the strips 14 and 21 through the metal parts of the gear train and conductor 22 to 95 said part 7. Then the toy will begin to move again and will pass from the section 7 on to the main part. By adjusting the speed of the motor 5, the rotation of the disc 8 can be controlled to cause the toy to 100 stop every time it reaches the section 7 or it may be caused to revolve one or more times 110

around the track and then to stop on the section 7.

It is thought from the foregoing description that the advantages and novel features 5 of my invention will be readily apparent.

I desire it to be understood that I may make changes in the construction and in the combination and arrangement of the several parts, provided that such changes fall within 10 in the scope of the appended claims.

What I claim is:—

1. In an electric toy, a track comprising a third rail having an insulated portion, a motor, means for supplying current to the motor and to both the sections of the third rail and a switch for controlling the flow of current to the insulated section, such switch consisting of a disc of insulated material and having a conducting strip therein, a contact arranged to engage the strip during the rotation of the disc, means for connecting the contact with the major part of the third rail, means for connecting the conducting

strip with the insulated section of the third rail and means for driving the disc from the 25 motor.

2. An electric toy comprising a track, a third rail having an insulated section, a motor, means for supplying current to the motor and to both parts of the third rail, 30 rheostats in the circuits of the motor and the third rail, a gear casing, means for driving the gears therein from the motor, a disc of insulated material driven from the gears, a conducting strip carried by the disc, a slide- 25 able contact engaging the strip during the rotation of the disc, an adjustable spring contact engaging the first contact, means for electrically connecting the spring contact with the major portion of the third rail and 40 means for electrically connecting the conducting strip through the gears and a conductor with the insulated section of the third rail.

In testimony whereof I affix my signature.

JOSEPH A. GRABENSTEIN.
